UNITED STATES PATENT OFFICE.

OLOF S. BURMAN, OF MINNEAPOLIS, MINNESOTA.

FAUCET AND ATTACHING BRACKET.

1,398,767.

Specification of Letters Patent. Patented Nov. 29, 1921.

Application filed February 10, 1921. Serial No. 443,832.

To all whom it may concern:

Be it known that I, OLOF S. BURMAN, a citizen of the United States, residing at Minneapolis, in the county of Hennepin and State of Minnesota, have invented certain new and useful Improvements in Faucets and Attaching Brackets; and I do hereby declare the following to be a full, clear, and exact description of the invention, such as

10 will enable others skilled in the art to which it appertains to make and use the same.

My invention has for its object to provide an extremely simple and highly efficient faucet and bracket for attaching the same to a laundry tray or other support.

To the above end, the invention consists of the novel devices and combinations of devices hereinafter described and defined in the claims.

20 In the accompanying drawings, which illustrate the invention, like characters indicate like parts throughout the several views.

Referring to the drawings:

25 Figure 1 is a view partly in front elevation and partly in vertical section illustrating the invention attached to a laundry tray having two compartments;

Fig. 2 is a view principally in side elevation with the laundry tray sectioned on the line 2—2 of Fig. 1; and

Fig. 3 is a rear elevation of the attaching bracket.

The invention, as illustrated, includes a double faucet, in the body of which are laterally spaced hot and cold water compartments 4 and 5, respectively. These compartments 4 and 5 are open at their tops and have internal screw threads to receive the 35 screw-threaded lower ends of vertically disposed hot and cold water supply pipes 6 and 7, respectively. Below the compartments 4 and 5 is a common mixing chamber 8, with which said compartments have communication through ports 9 normally closed by valves 10 attached to horizontal stems 11 which work in stuffing boxes 12 on opposite sides of the body of the faucet. These stems 11 are alined, extend in opposite directions and have handles 13 applied to their outer ends.

On the bottom of the body of the faucet is a depending centrally located nipple 14 on which is mounted, as shown, by screw-threaded engagement, a swinging nozzle 15

with which the mixing chamber 8 has communication through said nipple 14. Integrally formed on the bottom of the body of the faucet, on opposite sides of the nipple 14, is a pair of depending horizontally elongated anchor lugs 16 that are substantially round in cross section and connected to the body of the faucet by short necks.

The invention also includes a bracket for attaching the faucet to a support, which, as illustrated, is a laundry tray 17 having two compartments. This bracket includes two edgewise spaced sets of upper and lower co-operating pairs of inner and outer jaws. The upper inner and outer jaws are indicated by the numerals 18 and 19, respectively, and the lower inner and outer jaws are indicated by the numerals 20 and 21, respectively. The jaws 18 and 20, and the jaws 19 and 21, of each set, are integrally formed, and the jaws 18 and 20 of the two sets are connected by a tie-bar 22. It will be noted that the jaws 18 and 20, of both sets, and the tie-bar 22 are in the form of a single H-shaped casting. For the sake of convenience, the jaws 18—20 and 19—21 will hereinafter be termed fixed jaws and movable jaws, respectively.

Each set of fixed and movable jaws is intermediately connected by a nut-equipped bolt 23. These bolts 23, at their heads, are square and fit correspondingly formed seats in the fixed jaws 18 and 20 to hold the same from turning while their nuts are applied or removed therefrom. The upper or free ends of the jaws 18 and 20 have segmental co-operating seats 24 adapted to receive and hold the anchor lugs 16, as best shown in Fig. 3. Each set of jaws 20 and 21 is adapted to embrace the back of the tray 17 with its central partition between the two sets thereof. The jaws 20 are provided with shoulders 25 alined with the under edge of the tie-bar 22, and which tie-bar, together with said shoulders, rest upon the upper edge 90 of the back and partition of the tray 17 and support the attaching bracket therefrom. The fixed jaws 20, below their shoulders 25, have flat engagement with the respective face of the tray 17 throughout their entire 95 length, and the inner faces of the movable jaws 21 are made concave to clear the back wall of said tray so that only their free or lower ends engage said back wall at a point substantially midway between the shoulders 100 105 110

25 and the lower ends of the fixed jaws 20. Obviously, by tightening the nuts on the bolts 23, the jaws 18 and 19 are securely clamped onto opposing faces of the anchor 5 lugs 16, and the jaws 20 and 21 are clamped onto opposing faces of the back of the tray 17.

It will be noted that the several chambers in the body of the improved faucet, together 10 with the nipples for the stuffing boxes and nozzle and also the anchor lugs, are all located in the same plane, making a very simple casting that can be manufactured at a comparatively small cost and, at the same 15 time, is very compact. The H-shaped design of the attaching bracket permits the same to straddle the central partition of the two-compartment tray 17 and also affords a clearance for the nozzle 15, so that the same 20 may be swung from one side of said partition to the other to discharge water into either of the compartments in the tray. The attaching bracket securely holds the faucet in a position over the tray against movement 25 in all directions. By the use of the improved faucet and attaching bracket, a large amount of labor and material is saved in installing a hot and cold water supply for laundry trays.

30 What I claim is:

1. The combination with a faucet having a swinging nozzle, of a support, and an attaching bracket having pairs of clamping jaws engageable with the faucet on each side 35 of the swinging nozzle and with the support.

2. The combination with a faucet, of a support, and an attaching bracket having pairs of clamping jaws engageable with the 40 faucet and the support, one of the jaws of

the pair engaging the support being laterally offset to afford a supporting shoulder.

3. The combination with a faucet having an anchor lug, of a support, and an attaching bracket having jaws engageable with 45 said anchor lug and support.

4. The combination with a faucet having a swinging nozzle and a pair of anchor lugs located one on each side of said nozzle, of an H-shaped attaching bracket having jaws 50 engageable with said anchor lugs.

5. The combination with a faucet having a swinging nozzle and a pair of anchor lugs located one on each side of said nozzle, of a support, and an H-shaped attaching bracket 55 having jaws on its uprights engageable with said anchor lugs and a support.

6. The combination with a faucet having a swinging nozzle and a pair of anchor lugs located one on each side of said nozzle, of a support, and an H-shaped attaching bracket 60 having jaws on its uprights engageable with said anchor lugs and a support, said bracket also having a supporting shoulder.

7. The combination with a faucet having a swinging nozzle and a pair of anchor lugs located one on each side of said nozzle, of an H-shaped attaching bracket having upper and lower fixed jaws on its uprights, upper and lower movable jaws coöperating 70 with the fixed jaws, and nut-equipped bolts connecting the movable jaws to the fixed jaws, the coöperating movable and fixed jaws being adapted to be clamped onto said anchor lugs and said lower fixed and movable jaws being adapted to be clamped onto a support.

In testimony whereof I affix my signature.

OLOF S. BURMAN.
